PORTABLE MANIFOLD AND
HOSE STANDCharles Shaffer, Philip E. G. Hansen, and
Louis J. Schimmöller, New York, N. Y.

Application March 13, 1945, Serial No. 582,477

6 Claims. (Cl. 48—190)

(Granted under the act of March 3, 1883, as
amended April 30, 1928; 370 O. G. 757.)

1

The invention described herein may be manufactured and used by or for the Government of the United States of America for governmental purposes without the payment of any royalties thereon or therefor.

This invention relates to oxy-acetylene welding equipment and more particularly to improvements in manifolds and hose stands for oxy-acetylene equipment.

An object of this invention is to provide a portable manifold having outlets for combustible gases.

A further object is to provide a portable manifold with convenient racks for supporting gas-carrying hose.

A still further object is to decrease the necessary length of gas-carrying hose.

Another object is to increase the safety of operating a gas welding unit wherein the gas-carrying hose is of considerable length.

Further objects and advantages of this invention, as well as its construction, arrangement and operation, will be apparent from the following description and claims in connection with the accompanying drawings, in which

Fig. 1 is a view, in perspective, of a horizontal type stand, showing a preferred embodiment of this invention;

Fig. 2 is a view of a modification showing a "candlestick" or vertical type stand similar in operation to the horizontal stand shown in Fig. 1;

Fig. 3 is a detailed drawing of the manifold coupled to the pressure gage and reducing valve; and

Fig. 4 is a schematic diagram showing two portable manifolds in operation at a shipyard.

Similar numerals refer to similar parts throughout the several views.

In the construction of building ways or huge ships such as aircraft carriers and battle-ships, there is always present the problem of conveying the oxygen and acetylene or other suitable combustible gases from the main source of supply to the ship or work station.

In order to overcome the need for long leads from the main source of gas to the work station, gas bottles or tanks of varying sizes were heretofore brought near the work station and discarded or removed when empty. However, when the need for a continuous supply of combustible

gases is great and immediate, as in the repair of a ship that must be returned to action as soon as possible, the constant replacement of empty tanks with filled tanks becomes an annoying and often critical waste of time.

The present invention surmounts these difficulties inherent in the use of such bottles and tanks by providing a portable manifold having conveniently spaced racks thereon for supporting gas-carrying hose and permitting a direct attachment to the main or controlling source so that a continuous supply of gas is always available.

Fig. 1 shows a portable manifold consisting of a rigid base 10 of any suitable material mounted on rollers 11 with two inverted V-shaped supports 12 secured to the base 10. The horizontal cross pieces 13 and transverse bars 14 and 15 are elements that complete the frame work to which an oxygen manifold 16 and an acetylene manifold 17 are attached.

Mounted on the oxygen manifold 16 and acetylene manifold 17 are pressure gages 18, reducing valves 19, and shut-off cocks 20. A gage 18, valve 19, and cock 20 can be associated with each outlet of the manifold. The cock 21 is the main shut-off for the oxygen supply leaving the portable manifold, and the cock 22 is a similar shut-off for the acetylene supply. The flexible hoses 23 and 24 are respectively the oxygen and acetylene leads that connect the portable manifold with the main source of gas 25 (shown in Fig. 4). A support, consisting of a vertical metal stanchion 26 and a U-shaped member 27 on which the coiled surplus of the main hoses 23 and 24 are hung, is welded, bolted or otherwise secured fixedly to a plate 28 that connects the two top horizontal bars 13 and the two inverted V-shaped supports 12.

Numbered upright arms 29 forming hose supports are placed at spaced intervals along the horizontal bars 13 and also on the transverse bars 14 that are disposed approximately in the center of the framework as shown in Fig. 1. These upright arms support the hoses 30 that connect the portable manifold to the welders' torches used near the working area.

A roof 31 is secured to the top of the two inverted V-shaped supports 12 and acts as a

weather-shield for the gages 18, pressure regulators 19, and shut-off cocks 20. The hoses 32 and 33 are the oxygen lead and acetylene lead, respectively, and connect with another portable manifold not shown in the drawing.

The "candlestick" type modification shown in Fig. 2 is used in close quarters or in confined areas wherein the use of the horizontal type would be prohibitive because of lack of space. It is supplied by an oxygen hose 34 and an acetylene hose 35, which carry the gases from the main source into the portable manifold through vertical manifolds 36 and 37. The pressure gages 38, the reducing valves 39, the shut-off cocks 40, and nipples 41 connected to these manifolds 36 and 37 are similar to the corresponding devices mentioned in the description of the horizontal type portable manifold shown in Fig. 1. The oxygen manifold 36 and acetylene manifold 37 are secured to a rigid base 42 and rollers 43 are attached to the underside of the base 41 so that the entire manifold can be moved easily from station to station. The outlets 44 and 45 are respectively the oxygen and acetylene outlets to which hoses are attached to connect with another portable manifold.

A stanchion 46 is secured to the base 42. The said stanchion runs parallel to the manifolds 36 and 37 and all three, stanchion and manifolds, are secured to a substantially circular lid 47, said lid 47 serving as a weather-shield for the gages 38, valves 39, and cocks 40. To support the incoming and outgoing main acetylene and oxygen leads, U-shaped racks 48 are secured fixedly to the substantially circular lid 47. To further brace the manifolds 36 and 37 and the stanchion 46, a plate 49 is secured to these three elements below the lid 46.

Fig. 4 is a schematic diagram showing the portable manifolds of Figs. 1 and 2 in operation. The object to be worked upon is usually at a fixed station, such as a ship in port or a building under construction. Consequently, the distance from the main source of gas supply to the immediate environs of the work station is of a known and relatively fixed length. The two lengths of hose 23 and 24 serve as the connecting links between the main sources of gas 25 and the portable manifold.

The hoses 30 are now tapped off from the portable manifold to the ship or work station. As many pairs of oxygen and acetylene outlets can be used as is desired, but the use of too many outlets on one portable manifold tends to make the latter cumbersome and unwieldy. In one embodiment of the invention, a total of ten outlets, five for oxygen and five for acetylene, was found satisfactory.

When the portable manifold is in the vicinity of the working area, the hoses 30 are connected to the appropriate nipples of the portable stand and these hoses 30 are in turn connected to the welders' hand torches. Should some of the hoses 30 be idle temporarily, they are coiled about the numbered uprights 29. Should it be necessary to do work in the hold or lower compartments of the ship, the length of the main leads 23 and 24 can be increased so that the hoses 30 can be sufficiently short to prevent them from getting fouled up, yet long enough to permit the individual welders reasonable play while welding.

Thus, by shortening the distance between the manifold and the point of welding, it takes little time to trace the hoses 30, especially when a leak takes place in the hose and it is necessary to shut

off the proper cock on the portable manifold quickly.

In Fig. 4, a portable manifold of the "candlestick" or vertical type of Fig. 2 is shown connected in series with the horizontal type of Fig. 1. Thus it is possible to maintain a constant source of gas from a central source to any number of ships or stations by using any number of portable manifolds connected in series.

Modern fighting vessels such as aircraft carriers and battleships are over 800 feet in length. It is not unusual to make oxy-acetylene welds on parts of a ship that are 1000 feet or more from the main gas source. The present invention provides a continuous yet flexible supply of combustible gases from the main source.

The use of these portable manifolds causes a great saving of hose. Previously, in order to maintain a continuous supply of gas from the main source, hoses were attached to the individual nipples of the stationary manifold and were extended to reach to the working area. The present invention requires only two hoses from the main source to the vicinity of one working area. Moreover, not only is a continuous supply of gas maintained by using this portable manifold, but the advantages that accrue from the use of the bottles and tanks are also present, namely, closeness to the shut-off cocks and reducing valves. Such proximity serves to speed-up the tracing of the leads.

Various modifications and changes can be made in the subject device without departing from the scope of the invention.

We claim:

1. In a distribution device for supplying gases from a main source of combustible gases, a movable carriage framework having multiple manifolds thereon, means for connecting flexible conduits to said manifolds for transporting said combustible gases to said manifolds, and gas regulators and gas outlets disposed at spaced intervals along said manifolds.

2. In a distribution device for supplying gases from a main source of combustible gases, a movable carriage framework, a plurality of manifolds secured to said framework, uprights secured fixedly to longitudinal and transverse bars comprising part of said framework, gas regulators and gas outlets disposed at spaced intervals along said manifolds, and means for attaching flexible hoses to said gas outlets.

3. In a distribution device for supplying gases from a main source of combustible gases, a movable carriage framework comprising a base, inverted V-shaped members mounted on said base, transverse and longitudinal elements secured to said V-shaped members, a plurality of manifolds secured to said movable carriage framework, gas regulators and gas outlets disposed at spaced intervals along said manifolds, and means for connecting flexible conduits to said manifolds for transporting said combustible gases to said portable manifolds.

4. In a distribution device for supplying gases from a main source of combustible gases, a movable carriage framework comprising a base, inverted V-shaped members mounted on said base, transverse and longitudinal elements secured to said V-shaped members, a plurality of manifolds secured to said movable carriage framework, gas regulators and gas outlets disposed at spaced intervals along said manifolds, means for connecting flexible conduits to said manifolds for transporting said combustible gases to and from said

manifolds, and U-shaped members secured to the inverted V-shaped members for supporting the coiled surpluses of said flexible conduits.

5. In a distribution device for supplying gases from a main source of combustible gases, a movable carriage framework comprising a base, inverted V-shaped members mounted on said base, transverse and longitudinal elements secured to said V-shaped members, a plurality of manifolds secured to said movable carriage framework and having gas regulators and gas outlets attached thereto, means for connecting flexible conduits to said manifolds for transporting said gases to and from said manifolds, racks for receiving the coiled surpluses of the flexible transporting means secured to said movable carriage framework, and a protective weather-shield secured to the tops of the V-shaped members.

6. In a distribution device for supplying gases from a main source of combustible gases, a carriage base, a vertically-disposed supporting structure connected to said base, a plurality of vertically-disposed gas manifolds secured to said

structure, gas inlet connections on said manifolds for attachment to flexible gas supply conduits, a plurality of gas outlet connections for attachment of flexible work conduits disposed at spaced intervals along said manifolds, and gas regulators associated with said gas outlet connections.
